Primary Examiner—A. Hugo Word*Assistant Examiner*—R. Seifert*Attorney, Agent, or Firm*—Richard C. Litman[57] **CLAIM**

The ornamental design for a football key ring, as shown and described.

DESCRIPTION

FIG. 1 is a top perspective view of a football key ring showing my new design;

FIG. 2 is a top plan view thereof;

FIG. 3 is a bottom plan view thereof;

FIG. 4 is a right end elevational view thereof;

FIG. 5 is a left end elevational view thereof;

FIG. 6 is a rear elevational view thereof; and,

FIG. 7 is a front elevational view thereof.

The broken line showings in FIGS. 1, 2, 4, 5, and 7 represent sports indicia and/or keys and form no part of the claimed design.

FIG. 1

FIG. 2

FIG. 6

FIG. 7
